CLAIM

The ornamental design for a cosmetic product container, as shown and described.

DESCRIPTION

FIG. 1 is a front elevational view of a cosmetic product container showing my new design;

FIG. 2 is a left side elevational view thereof;

FIG. 3 is a right side elevational view thereof;

FIG. 4 is a rear elevational view thereof;

FIG. 5 is a top plan view thereof; and,

FIG. 6 is a bottom plan view thereof.

The broken lines in the drawing depict portions of the cosmetic product container that form no part of the claimed design.

The stippling in FIGS. 1-6 shows contrast in appearance.
